(57) **CLAIM**

The ornamental design element for a signal light for automobiles, as shown and described.

DESCRIPTION

FIG. 1 is a view of the ornamental signal light for automobiles in an environment (front view).

FIG. 2 is a view of the ornamental signal light for automobiles in an environment (rear view).

FIG. 3 is an enlarged view of FIG. 1, front view, right side, along lines 3-3'; and,

FIG. 4 is an enlarged view of FIG. 2, back view, left side, along lines 4-4'.

An enlarged front, left side view is omitted, because it is symmetrical to the front, right side view. An enlarged back, right side view is omitted, because it is symmetrical to the back, left side view.

The broken line showing of the automobile is included for the purpose of illustrating the claimed design and forms no part of the claimed design.
